(57) **CLAIM**

The ornamental design for a side table, as shown and described.

DESCRIPTION

FIG. 1 is a front, top, and right perspective view of a side table, showing my new design;

FIG. 2 is a rear, bottom, and left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, top, and right perspective view of the side table, shown with the drawer in an open configuration; and, FIG. 10 is a rear, bottom, and left perspective view shown with the drawer in an open configuration.

The broken lines in the figures illustrate portions of the side table that form no part of the claimed design.
